UNITED STATES PATENT OFFICE.

EMIL OFFENBACHER, OF MARKT-REDWITZ, GERMANY.

DESIGN FOR SHEET OR PLATE GLASS.

SPECIFICATION forming part of Design No. 30,085, dated January 31, 1899.

Application filed December 14, 1898. Serial No. 699,268. Term of patent 14 years.

To all whom it may concern:

Be it known that I, EMIL OFFENBACHER, a subject of the Emperor of Germany, residing at Markt-Redwitz, in the Kingdom of Bavaria, 5 Empire of Germany, have invented a certain new and original Design for Sheet or Plate Glass, of which the following is a specification.

My invention relates to a new and original design for sheet and plate glass the surface 10 of which is roughened or formed into ridges.

The leading features of my design are the special arrangement or configuration or form of the ridges on the face of the glass, such arrangement, configuration, or form consisting 15 of a number of irregular scrolls or spirals, the lines of which are approximately parallel, with a series of wave-like lines occupying the space between such irregular scrolls or spirals, such lines extending approximately parallel 20 to said scrolls or spirals.

In the accompanying drawings, forming part of the present specification, I illustrate my new and original design.

In the drawings, Figure 1 is a plan view of

a portion of a plate of glass embodying my 25 new and original design, and Fig. 2 a cross-sectional view of the same.

The face of the glass is provided with a series of ridges *a*, which occupy its entire surface. The ridges *a* are formed into a series 30 of irregular scrolls or spirals *b*, the lines constituting which extend approximately parallel. Between the spirals *b* the ridges *a* on the surface of the glass are arranged in groups *c*, constituting, essentially, each a series of approximately parallel ridges, which ridges also extend approximately parallel to the lines constituting scrolls or spirals *b*. 35

Having now described my invention, what I claim is—

The design for sheet and plate glass, substantially as herein shown and described.

This specification signed and witnessed this 22d day of October, 1898.

EMIL OFFENBACHER.
